GRAVITY-TRAP DRY SEPARATOR.

1,131,081.

Specification of Letters Patent.

Patented Mar. 9, 1915.

Application filed March 17, 1914. Serial No. 825,272.

To all whom it may concern:

Be it known that I, DAVID F. PLATNER, a citizen of the United States, residing at Monterey, in the county of Monterey and State of California, have invented new and useful Improvements in Gravity-Trap Dry Separators, of which the following is a specification.

This invention relates to machines for separating gold and other metalliferous values for crushed ores, gravel and the like, by dry process, the special object of the invention being to provide a dry separator and concentrator of this character which is simple, efficient, of large capacity, reversible and adjustable, all as will appear hereinafter.

The invention consists of the parts and the construction and combination of parts as hereinafter more fully described and claimed, having reference to the accompanying drawings, in which—

Figure 1 is a longitudinal section of the invention on the line X—X, Fig. 3. Fig. 2 is a fragmentary plan view, with parts broken away. Fig. 3 is an end elevation. Fig. 4 is a sectional view of a riffle. Fig. 5 is a detail of a staple.

A represents a gravity trap box pivotally mounted centrally, as at 2, on flexible standards 3—3' secured to a rigid frame or jarring posts 4—4'; the box A being adapted to be given an oscillating or reciprocating lateral movement by suitable means, as a lever 5, linked to the standard 3 at one end and linkedly connected to a crank 6 at the other end. The crank 6 is rotated in any suitable manner so as to rock the lever 5 to shake the gravity box A from side to side, and jar it against the jarring posts 4—4'. Manifestly any other means may be employed to effect this necessary jar or vibration of the box.

The top of the box is covered with a screen 7 and an intermediate screen 8 is disposed thereunder. The bottom of the box is provided with a special form of transversely extending riffles 9 which are constructed and arranged as shown in Figs. 1 and 4. These riffles 9 are each composed of a sheet-metal plate bent to form a rectangular trough with a flat bottom and straight sides a—a'; the upper edge of the side a being bent horizontally and outward, as

shown at b and the portion b having an upwardly projecting vertical lip c. The riffles are disposed on each side of the center of the box, with the parts b—c extending toward the center, as shown in Fig. 1. The lips c terminate a short distance below the lower screen 8. The bottom of the box A, between the riffle plates 9, is studded with staples 10, Figs. 2 and 5, which are so staggered and otherwise disposed in relation to each other as to thoroughly rake the materials being treated vertically and horizontally, thus preventing the materials packing between the riffles in seams or strata.

Material to be treated is fed centrally, at 13, and the box A may be tilted and supported at any desired angle in either direction on the pivotal bearing 2, being retained in any desired position by suitable means, as the adjustable brackets 11, upon which either end of the top may be supported; 75 rollers 12 on the box A being adapted to bear on the brackets or seats 11. This arrangement permits of the floor of the box A being inclined at any desired pitch in either direction, and permits the box to be vibrated 80 while in any position. By removing the brackets 11 from their support, the box A may be inverted when desired, and when cleaning. Each end of the box A is open so as to allow the lighter materials or 85 gangue which pass over the riffles 9 to be discharged when the box is in inclined position. The box is divided at its center by a partition 14 so that when inclined, only the waste material or gangue running over the 90 riffles on the lower half of the box will be allowed to escape; the trapped material and values on the upper half being confined within and between the riffles until the box is later inverted in cleaning up.

In operation, the material to be treated is delivered to the screen 7 in any desired manner, as through a hopper 13, and on passing through the screens 7—8 is deposited between the riffles 9 and is subjected to jarring 100 action which causes the heavier or mineral particles to settle to the bottom of the box A, while the lighter material or gangue passes over the riffles to be discharged when the box is inclined, as before described, the 105 values remaining between the upright plates of the riffles 9, to be removed for further treatment, as desired.

The invention is shown in the drawings as a unit, but it is obvious that a series of boxes A can be mounted side by side, either on one or separate pivots, and be subjected to jarring motion simultaneously or independently.

For this device I claim the following special points of advantage over all other riffles, viz: First, the construction of the 10 riffles 9 gives it a stronger dividing force for all material passing into the gravity trap saving boxes formed between the riffles. Second, the construction of the riffle 9 gives the gravity trap an additional storage capacity for storing all gold passing into the 15 gravity trap boxes. Third, the construction of the riffle placed transversely in the box discharges the gangue matter, and deposits the gold or other metalliferous values 20 into the storage trap of the gravity trap boxes.

The gravity trap box may be revolved on its pivot 2 for cleaning up purposes. When 25 in operation it is checked and held in place by the series of stop guides 11 and roller arms 12 projecting from the side of the box.

The wire precipitators 10, as shown in Fig. 2, prevent the compacting of the material distributed into the boxes, and help 30 precipitate the gold carried therein.

Having thus described my invention, what I claim and desire to secure by Letters Patent is—

1. In a concentrator, a box, a series of 35 spaced U-shaped riffles having their bases secured to the box bottom, one of the sides of the riffles being extended outwardly and then upwardly to form upper L-shaped parts which extend toward the center of the box,

and staples in the box bottom some of which 40 underlie the L-shaped parts of the riffles.

2. In a concentrator, a frame, a box mounted in the frame in spaced relation to the sides thereof, flexible standards connected to the frame and to the center of the 45 box for pivotally supporting the latter, means to movably and adjustably engage the ends of the box to permit the latter to be set at varying inclinations by moving the box about its pivotal points, and means connected to one of the standards for reciprocating same.

3. In a concentrator, a frame, a box mounted in the frame in spaced relation to the sides thereof, flexible standards connected to the frame at their lower ends and to the center of the box at their upper ends so as to allow the box to be tilted at its ends with respect to the standards and about its 50 pivotal points, means to reciprocate one of the standards, and means to slidably engage the box ends upon the angle of inclination of same being varied.

4. In a concentrator, a frame, a box in the frame spaced therefrom, means to movably 55 support the box to allow same to be adjustably tilted or inclined relative to the support, means to reciprocate the box, and means to movably support the box in its adjusted inclined position.

In testimony whereof I have hereunto set my hand in the presence of two subscribing witnesses.

DAVID F. PLATNER.
